his Attorney.

UNITED STATES PATENT OFFICE.

ELLSWORTH MARSHALL RUST, OF WASHINGTON, DISTRICT OF COLUMBIA, ASSIGNOR
TO THE RUST ENGINEERING COMPANY, OF PITTSBURGH, PENNSYLVANIA, A COR-
PORATION OF DELAWARE.

MOLD.

Application filed February 25, 1925. Serial No. 11,509.

To all whom it may concern:

Be it known that I, ELLSWORTH MARSHALL RUST, a citizen of the United States, and resident of Washington, in the District of Columbia, have invented certain new and useful Improvements in Molds, of which the following is a specification.

This invention relates to molds and more particularly to sectional molds used in building concrete chimneys and similar monolithic concrete structures.

The principal object of this invention is to provide a mold of the above class with a novel means for mounting and supporting step irons to be embedded in the finished article, to form a ladder.

Another object is to provide a mold of the above class with one or more of its sections provided with the means for mounting and supporting the step irons, so that the section may be used in molds of various sizes.

A further object is to provide a mold having the novel construction, arrangement, and combination of parts hereinafter described and illustrated in the accompanying drawings.

In the drawings:

Figure 1 is an elevation, partly in section, showing a tapering sectional mold embodying the novel features of this invention.

Figure 2 is a partial plan of the mold of Figure 1.

Figure 3 is an enlarged elevation of a portion of the mold section having the step iron mounting therein.

Figure 4 is a fragmentary sectional elevation through the mold, showing the step iron mountings.

Figure 5 is a sectional plan showing a mounted step iron.

Referring more particularly to the drawings, the letter A designates a completed portion of a circular chimney constructed with my improved form of mold B, which is shown assembled above or on top of the completed portion of the chimney. The mold B is composed of a plurality of detachably connected sheet metal sections 2. The mold B is adapted to cooperate with a segmental, annular core C to form a closure for receiving the concrete.

The mold B, when in use, is suspended from an annular adjusting ring D, which is made in sections, and when in operative position, the ring D is adjustably suspended

or hung by suitable tackle, such as a block and fall from a scaffold or arms on the upper end of the scaffold.

The scaffold, which may be of any of the several old and well known constructions, and which is not shown, will be built on the inside or outside of the chimney A and will extend through the annular core C to a point somewhat above the completed portion of the chimney, the scaffold being lengthened from time to time in keeping its upper end above the finished part of the chimney A and mold B so as to enable the mold B to be lifted and reassembled above the upper end of the formed part of the chimney.

One of the sections 2 of the mold B is provided with a plurality of transversely arranged elongated rectangular openings or slots 4, spaced equi-distant vertically. The openings or slots 4 are provided to permit the mounting of U-shaped step irons 5 in the mold so that their ends will project into the concrete receiving space and their step portions will project outwardly from the mold. With the step irons mounted in the mold, as described above, their ends will be surrounded by and embedded in the concrete of the chimney as the concrete is poured thus furnishing a continuous ladder or line of steps up the side of the chimney when it is completed.

The section 2 of the mold having the openings 4 therein is reinforced around and adjacent each of the openings 4 by reinforcing plates 6, which are provided with an opening or slot 7 of the same shape and size as the openings 4. The plates 6 are positioned on the outer surface of the mold with their openings 7 in alignment with the openings 4 and are fixedly secured in position by rivets 8.

A removable supporting and locking plate 9 is provided for each of the step iron openings, and comprises an elongated plate member having vertically arranged open ended slots 10 opening upwardly from its lower edge. The plates 9 are mounted over the reinforcing plates 6 and the slots 10 are adapted to receive the side arms of the step irons. The slots 10 are of a width adapted to snugly engage the side arms of the step irons 5, and the plates 9 are provided with a plurality of elongated openings or slots 12 to receive bolts or screws 13 which are

screwed into threaded apertures 14 in the plates 6 to lock the plates 9 in position. The slots 12 are so positioned that the closed end of the step iron receiving slots 10 will engage the step irons when the bolts or screws 13 are screwed home. The slots 12 also permit the plates 9 to be adjusted transversely of the mold to position the step irons in time, and serve to lock the step irons in position when the screws 13 are screwed home:

In order to assure proper and equal spacing of the step irons 5 outwardly from the finished chimney a spacing timber 15 or 15, other similar spacing member is preferably inserted between the outer face of the mold and the step irons 5, and all the step irons positioned so as to contact with said member 15.

20. In operation the step irons 5 are passed through the openings 4 in the mold section from the rear of the mold; the plates 9 are then mounted in position, the step irons lined up, and the bolts or screws 13 are then 25 tightened to lock the step irons in position.

While I have shown and described only one embodiment of my invention it will be understood that I do not wish to be limited to the several details thereof, since changes 30 in design, construction and combination of the various elements will readily suggest themselves to those skilled in the art and may be made without departing from the scope of my invention as defined in the appended claims.

I claim:

1. In a sectional mold composed of a plurality of sections and used in building concrete chimneys and similar monolithic concrete structures, a section provided with a plurality of openings adapted to permit the mounting of step irons so that portions of said irons project into said mold, to be surrounded by and embedded in the concrete 40a put in the mold, and other portions project outwardly from said mold to form step portions, and means for supporting said irons in position while said mold is being filled with concrete.

45. 2. In a sectional mold composed of a plurality of sections and used in building concrete chimneys and similar monolithic concrete structures, a section provided with a plurality of openings adapted to permit the mounting of step irons so that portions of said irons project into said mold, to be surrounded by and embedded in the concrete put in the mold, and other portions project outwardly from said mold to form step portions, and means detachably mounted on said section for engaging and locking said irons in position.

50. 3. In a sectional mold composed of a plurality of sections and used in building concrete chimneys and similar monolithic con-

crete structures, a section provided with a plurality of openings adapted to permit the mounting of step irons so that portions of said irons project into said mold, to be surrounded by and embedded in the concrete 70 put in the mold, and other portions project outwardly from said mold to form step portions, reinforcing members secured to said section to reinforce said section adjacent said openings, and means for supporting 75 and locking said irons in position.

4. In a sectional mold composed of a plurality of sections and used in building concrete chimneys and similar monolithic concrete structures, a section provided with a plurality of openings adapted to permit the mounting of step irons so that portions of said irons project into said mold, to be surrounded by and embedded in the concrete 80 put in the mold, and other portions project outwardly from said mold to form step portions, reinforcing plates having openings therein adapted to be aligned with the openings in said section, said plates being secured to said sections, and means co-operating with said plates for supporting 85 and locking said irons in position.

5. In a sectional mold composed of a plurality of sections and used in building concrete chimneys and similar monolithic concrete structures, a section provided with a plurality of openings adapted to permit the mounting of step irons so that portions of said irons project into said mold, to be surrounded by and embedded in the concrete 90 put in the mold, and other portions project outwardly from said mold to form step portions, reinforcing plates having openings therein adapted to be aligned with the openings in said section, said plates being secured to said sections, and supporting and locking plates detachably secured to said reinforcing plates and adapted to support and lock said irons in position.

6. In a sectional mold composed of a plurality of sections and used in building concrete chimneys and similar monolithic concrete structures, a section provided with a plurality of transversely arranged elongated slots adapted to permit the mounting of step irons so that portions of said irons project into said mold and other portions project outwardly from said mold to form step portions, reinforcing plates having openings therein duplicate in size and shape to the opening in said mold section and adapted to be aligned with said openings in said section, said plates being fixedly secured to said section, and supporting and locking plates detachably secured to said reinforcing plates and adapted to support and lock said irons in position.

In testimony whereof I have hereunto signed my name:

ELLSWORTH MARSHALL RUST.
